UNITED STATES PATENT OFFICE.

FRANK GARDNER, OF DALLAS, TEXAS.

DISPLACEMENT PUMP.

Application filed May 27, 1922. Serial No. 564,007.

To all whom it may concern:

Be it known that I, FRANK GARDNER, a citizen of the United States, residing at Dallas, in the county of Dallas and State 5 of Texas, have invented certain new and useful Improvements in Displacement Pumps, of which the following is a specification.

This invention relates to new and useful 10 improvements in displacement pumps.

The object of the invention is to provide a displacement pump for elevating liquids and employing fluid pressure as a motive force in such a manner as to attain certain 15 highly desirable results. A particular object of the invention is to provide a pump of increased capacity which will be economical in its consumption of fluid pressure and power and positive in its operation, 20 thus eliminating considerable waste which has been present in the displacement pumps now in use.

Another and important object of the invention resides in means for automatically 25 controlling the admission of high pressure motive fluid to and its exhaust from the displacement chamber. A still further object is to provide such a controlling means that will be free from springs and other variable- 30 operating elements and which will employ an over balancing of fluid pressures to effect its operation.

In carrying out the invention a displacement chamber is connected in the pipe line 35 thru which the liquid is to be elevated and has its lower end submerged so that said liquid will enter the chamber. The chamber has an automatic valve at its upper end connected with a high pressure fluid line 40 and is provided with two pistons of unequal areas whereby the pressure on one may overcome the pressure on the other and the piston reciprocated to control the flow of the high pressure motive fluid to 45 and from the displacement chamber.

A construction designed to carry out the invention will be hereinafter described together with other features of the invention.

The invention will be more readily understood from a reading of the following specification and by reference to the accompanying drawings, in which an example of 50 the invention is shown and wherein:

Fig. 1 is a vertical sectional view of the casing at the lower end of a well having

disposed therein a displacement pump constructed in accordance with my invention, a portion of said pump being shown in elevation,

Fig. 2 is an enlarged vertical sectional view of the controlling valve and the upper portion of the chamber, and

Fig. 3 is a plan view of the valve.

In the drawings the numeral 10 designates an elongated cylindrical displacement chamber having a nipple 11 entering its bottom at one side and surmounted by a valve seat 12 within the chamber. A screen or strainer 13 is attached to the lower end 70 of the nipple and with the chamber is submerged in the fluid in the casing 14 as is shown in Fig. 1. The seat 12 carries a ball valve 15 which closes to sustain the liquid flowing into the chamber.

A discharge pipe 16 extends down thru the chamber and has lower end terminating just above the valve seat 12. The discharge may be connected with any suitable conductor for elevating or conveying to the desired point or elevation, the liquid admitted to the chamber.

While I have illustrated a cased well, it is to be understood that this pump may be used to elevate or impel various liquids and not to be limited to use in a well. The pipe 16 has a valve seat 17 at its lower end carrying a ball valve 18 which supports the liquid pumped or displaced into the pipe. The valves operate alternately and any suitable type of valve may be employed.

A cap 19 is mounted on the upper end of the chamber and carries a valve housing 20 having an upper cylinder 20 and a lower cylinder 21 of considerably larger area than the upper cylinder. The upper end of the housing is screwed into a reducing collar 22 which receives the lower end of a high pressure air or other fluid line 23.

A passage 24 leads down the side of the cylinder 20 from the top of the housing and conveys the air. A large passage 25 with an angular offset at its upper end leads from the lower end of the cylinder 20 down thru the housing and communicates with the chamber 10. The passage 24 has ports 24' at its lower end entering the cylinder 20 diametrically opposite to the passage 25.

A solid piston 26 is mounted in the cylinder 20, while a larger piston 27 is mounted in the cylinder 21. These pistons are integral and may be made of one piece. The

cylinder 21 has its lower end open and receiving an inverted cap 28 which is screwed up into the said cylinder as is shown in Fig. 2. The upper edge of the cap serves as a stop to limit the downward movement of the piston. A plug 29 provided with a small aperture 30 is screwed into the bottom of the cap.

Intermediate its ends the cylinder 21 has 10 a series of ports 31 entering the passage 25 and registering with similar ports 32 in the piston 27, when the latter is at the upper end of its stroke. The upper end of the piston 27 is shouldered and abuts the upper 15 end of the cylinder 21, a relief port 33 in the cylinder wall acting to release the trapped air. The piston 27 has a transverse passage 34 and when the ports 32 register with the ports 31 this passage registers 20 with a port 35 in the cylinder wall which is connected with a pipe 36 discharging to atmosphere. This permits the air from the chamber to exhaust thru the passage 25 in order to relieve the pressure in the chamber 25 and permit the liquid to flow thereinto.

The piston 26 carries a needle valve 37 at its upper end adapted to seat in the lower end of a duct 38 in the top of the cylinder 20. A small duct 39 extends from the top of the 30 piston angularly down to register with an orifice 40 in the side wall of the cylinder to release trapped air from the top of the cylinder. So long as the pressure under the piston 27 is greater upward than the pressure 35 downward upon the needle valve 37, the pistons remain elevated and the ports 24' closed.

When sufficient fluid has leaked thru the 40 port 30 into the chamber 10 and escaped to the passage 25, to reduce the resistance offered to the piston 27, the fluid pressure acting on the valve 37 will start the pistons downward. As soon as the valve 37 is withdrawn from the duct 38 the high pressure 45 fluid passing thru the duct 38 will exert its full force upon the top of the piston 26. When the piston 27 comes to rest on the cap 28 the ports 31 and 35 will be closed and ports 41 in the piston 26 will register with 50 the ports 24; whereby the high pressure fluid will flow thru a transverse passage 42 to the passage 25 and from thence to the chamber 10.

The high pressure fluid entering the 55 chamber 10 will displace the liquid therefrom into the discharge pipe 16, seating the valve 15, and unseating the valve 18, whereby the liquid will be elevated in the pipe.

When the fluid pressure has exerted its 60 motive force the valve 18 will seat, thus supporting the column of fluid in the pipe 16. The motive fluid upon entering the chamber will begin to pass thru the port 30 into the cap 28 and will be built up to the point 65 where the pressure exerted owing to the

larger area of the piston 27, will overcome the pressure upon the top of the piston 26.

The pistons will be elevated so that the ports 24' will be closed as well as the lower end of the duct 38, thus cutting off the flow 70 of high pressure fluid thru the passage 25. At the same time the ports 31 will be opened permitting an exhaust thru ports 32, passage 34, port 35 and pipe 36.

The pistons are held at the extreme upper 75 end of their travel by a residual pressure in the cylinder 21, which however will be gradually reduced thru the escape of the fluid into the chamber 10 thru the port 30. Such reduction and escape will be slow so as to 80 give ample time for the liquid to flow from the nipple 11 past the valve 15 and fill the chamber to the liquid level therein. This timing may be controlled by substituting a larger or smaller cap 28 or by inserting another plug 29 with a larger or smaller port 30. It is also pointed out that any suitable means might be employed for exerting a fluid pressure against the under side of the 85 piston 27.

It will be seen that as soon as the residual 90 pressure in the cylinder 27 and cap 28 is reduced to a point below the pressure exerted upon the needle valve the pistons will start downward and the cycle repeated. The operation will be quite rapid and as soon as the chamber fills with liquid the same will be displaced therefrom, so that if provision is made for rapidly filling the chamber, the 95 pump will have a large capacity.

It is pointed out that the air or pressure fluid is not entirely exhausted from the cap and upper end of the chamber as the liquid does not rise to this point, and thus the remaining pressure is utilized in building up 100 the pressure to elevate the pistons. However, the parts are regulated so as to obviate back pressure against the inflowing liquid.

Various changes in the sizes and shape 105 of the various parts as well as modifications, may be made without departing from the spirit of the invention and within the scope of the appended claims.

What I claim is:

1. In a displacement pump, a displacement 115 chamber having a valved liquid inlet and a valved liquid outlet, a controlling valve mounted on the chamber and having a high pressure fluid passage extending therethrough and connecting with the chamber, a fluid actuated member in the valve alternately intercepting the passage of high pressure fluid thru said valve subject to fluid pressure at each end, and variable pressure controlling means at one end of 120 said member for governing the period for which a residual pressure is maintained at said end of said member.

2. In a controlling valve for a displacement pump, a valve housing having a high 125

pressure fluid passage therethrough and an exhaust, a piston reciprocating in said housing having means for alternately interrupting and opening said passage and also means 5 for closing said exhaust when said passage is open and opening said exhaust when said passage is closed, means for exerting an initial high pressure in the piston and for exerting the full pressure upon the upper 10 end of the piston after the initial movement thereof, and means for admitting a high pressure to the under side of the piston to over come the downward pressure and for retaining and gradually reducing a residual 15 pressure beneath the piston until overcome by the downward pressure.

3. In a controlling valve for a displacement pump, a valve housing having superposed cylinders, said housing having a high pressure fluid passage extending therethrough and intercepted by one of the cylinders, said housing having an exhaust opening in one of its cylinders, connected pistons operating in said cylinders and having 20 passages for opening said fluid passage and said port when registering therewith and arranged to close said fluid passage and port when said piston passages are out of registration therewith, and means for subjecting 25 said pistons alternately to unequal pressures, whereby said pistons are reciprocated.

4. In a controlling valve for a displacement pump, a valve housing having superposed cylinders, said housing having a high pressure fluid passage extending therethrough and intercepted by one of the cylinders, said housing having an exhaust opening in one of its cylinders, connected pistons operating 30 in said cylinders and having passages for opening said fluid passage and said port when registering therewith and arranged to close said fluid passage and port when said piston passages are out of registration therewith, and means for gradually reducing the 35 pressure at one end of the piston, whereby the pistons are held at rest for a period of time.

5. In a controlling valve for a displace-

ment pump, a valve housing having superposed cylinders, said housing having a high pressure fluid passage extending therethrough and intercepted by one of the cylinders, said housing having an exhaust opening in one of its cylinders, connected 50 pistons operating in said cylinders and having passages for opening said fluid passage and said port when registering therewith and arranged to close said fluid passage and port when said piston passages are out of 55 registration therewith, and the lower piston having a larger area and restricted means for admitting and exhausting a pressure fluid to the lower cylinder under the piston thereof having provision for varying the 60 rapidity of the passage of the fluid therethrough, the upper cylinder having an opening for admitting a high pressure fluid, and a needle valve closing opening when the upper piston is at the upper end of its stroke. 65

6. In a controlling valve for a displacement pump, a valve housing having superposed cylinders, said housing having a high pressure fluid passage extending therethrough and intercepted by one of the cylinders, said housing having an exhaust opening in one of its cylinders, connected pistons operating in said cylinders and having 70 passages for opening said fluid passage and said port when registering therewith and arranged to close said fluid passage and port when said piston passages are out of registration therewith, and the lower piston having a larger area and restricted means for admitting and exhausting a pressure fluid 75 to the lower cylinder under the piston thereof having provision for varying the rapidity of the passage of the fluid therethrough, the upper cylinder having an opening for admitting a high pressure fluid, and a needle valve closing opening when the upper piston is at the upper end of its stroke, and a removable closure for the lower cylinder providing for a variation of the 80 volume of fluid admitted to said cylinder. 95

In testimony whereof I affix my signature.

FRANK GARDNER.
